UNITED STATES PATENT OFFICE.

CARLOS A. MCNEIR, OF MINNEAPOLIS, MINNESOTA.

WATER-GRAVE FOR GAS-STOVES.

1,176,917.

Specification of Letters Patent.

Patented Mar. 28, 1916.

Application filed September 7, 1915. Serial No. 49,185.

To all whom it may concern:

Be it known that I, CARLOS A. MCNEIR, a citizen of the United States, residing at Minneapolis, in the county of Hennipin and State of Minnesota, have invented certain new and useful Improvements in Water-Grates for Gas-Stoves, of which the following is a specification.

My invention relates to water grates for 10 gas stoves and has for its object to provide a grate to take the place of the grate ordinarily furnished with gas stoves wherein there shall be cast integral means directly associated with the grate bars for heating water 15 from the heat ordinarily wasted in regular cooking operations.

The full objects and advantages of my invention will appear in connection with the detailed description thereof and are particularly pointed out in the claims.

In the drawings, illustrating the application of my invention in one form, Figure 1 is a plan view of my water heating grate. Fig. 2 is a longitudinal elevational section 25 of my grate taken on line 2—2 of Fig. 1 and a portion of a gas stove showing the relation of my grate to the gas stove and burners when my grate is applied to the same. Fig. 3 is a transverse elevational section of my 30 grate taken on line 3—3 of Fig. 1, a burner and a portion of cooking utensil.

A gas stove of ordinary construction having a separate grate for each pair of burners is illustrated in Fig. 2. The body 10 of the 35 same is equipped with a top 11 which receives my grate 12 and also supports a gas burner 13 and the necessary valves 14 and pipes 15 common to all forms of gas stoves. Burner 13 is shown as circular but any form 40 of burner will operate equally well.

My grate proper, shown isolated in Figs. 1 and 3, has a rectangular frame member 16 adapted to cover two burners and rests upon the top 11 and has a plurality of through 45 grate bars 17 and grate bars 18 open at 28 similar to the ordinary form of grate. A pair of hollow annular circuitous members 19 and 20 are united at 21 and are cast integral with grate bars 17 and 18 and below 50 the tops of the same, as clearly shown in Figs. 1 and 3. Member 19 is provided with a downwardly-projecting pipe connection 22 into which is screwed an inlet pipe 23, and member 20 is provided with an outwardly-projecting pipe connection 24 into which is 55 screwed an outlet pipe 25. The water passes

from a reservoir, not shown in the drawing, through pipe 23, through member 19, through connection 21, through member 20 and through pipe 25 back to said reservoir, 60 the water being heated in members 19 and 20.

As seen in Figs. 2 and 3, the burners 13 come somewhat below members 19 and 20, leaving spaces 26 between said burners and 65 said members, the flames issuing upward from said burners through central apertures 28 in the members 19 and 20 to reach the utensils 29 placed on top of grate bars 17 and 18. It will be noted that the lower surfaces 27 of members 19 and 20 are slightly curved and slope upward. This characteristic is of double value. Surfaces 27 submit partial areas to the outermost portion of the flames which with the ordinary form of 70 grate never come in contact with the utensils to be heated and are hence wasted. Secondly, the flames rising through apertures 28 cause a draft through spaces 26, which draft tends to deflect the flames from the 75 bottom of the receptacles 29 downward to completely surround members 19 and 20 and so effectively utilize the wasted heat in heating the water within said members. Any heat taken up by the grate bars 17 and 80 18 is quickly transferred to the water within members 19 and 20, thus keeping all portions of my grate at a temperature not greater than the boiling temperature of water, and so serious injury to the operator or 85 any substance left upon the grate cannot take place. Such grates may readily be substituted for the grates at present used with various forms and styles of gas stoves, and they will utilize to a greater degree the full 90 95 heating capacity of the combustible consumed.

I claim:

1. A grate for gas stoves comprising an integral casting consisting of a rectangular 100 frame portion adapted to be removably positioned on the top of a gas stove, said casting including a central portion embodying a hollow member extending longitudinally across the grate and including one or more 105 expanded portions having a central opening adapted to be positioned above the gas burner when the grate is set upon the stove, and a multiplicity of transverse parallel 110 grate bars connected with said frame and cast integral with said central member and with the expanded portions thereof.

2. A grate for gas stoves comprising an integral casting consisting of a rectangular frame portion adapted to be removably positioned on the top of a gas stove, said casting
5 including a central portion embodying a hollow member extending longitudinally across the grate and including one or more circular expanded portions having a central opening adapted to be positioned above the
10 gas burner when the grate is set upon the stove, and a multiplicity of transverse parallel grate bars, some of said bars being connected at both ends with the frame and at their centers with the longitudinal member
15 and some of the bars being connected at one

end only with the opposite sides of the frames and with the circular expanded portions, the other ends of said last named bars extending above said openings, all of said bars and said central member being adapted 20 to absorb the heat of the gas burner and transmit the same to water circulating within the hollow member.

In testimony whereof I affix my signature in presence of two witnesses.

CARLOS A. McNEIR.
